UNITED STATES PATENT OFFICE

GEORG PELTZ, OF LAUTAWERK/LAUSITZ, GERMANY

DEVICE FOR JOINING CARBON ELECTRODES

Application filed January 13, 1931, Serial No. 508,544, and in Germany January 23, 1930.

In electro-metallurgy more particularly in the manufacture of aluminium by reduction of bauxite, the use of electrode carbons causes very many difficulties especially when there are large separate anodes which consist either of one piece or of partial anodes which are joined together and operate as an unit. Such an anode should operate continuously in order that damage to the bath caused by 5 change, which take up much time, may be avoided. This can only be effected by providing a nipple. Simple carbon nipples which by means of screw threads or other arrangements press the anode parts together have failed because no means was provided to hold them so close together and to keep them so during operation, that there was no loosening. As soon as this unavoidable loosening occurs there are resistances to the current, the joining parts begin to overheat and the lower part of the anode reaches the bath before the nippled part has come near to the bath. The use of nipples of the same metal as was produced in the bath is also impossible because it is melted before the part of the anode which is secured by the nipple reaches the bath. Metals of higher melting point as nipple material lead to undesirable formation of alloy.

The combined iron carbon nipple which forms the subject of the present invention prevents the disadvantages referred to and ensures continuous and satisfactory operation. The nipple is illustrated by way of example in the accompanying drawing.

The device consists of:

a the carbon nipple, b the iron nipple, e the connecting rod between the iron nipple and the nut f an abutment bearing and g the nut provided with a hand wheel or knob. The carbon nipple as well as the anode carbon to be placed over it have grooves at c which receive rings of current conducting material.

In assembling the carbon nipple is screwed with its lower part into the anode section which is in operation. After this the various bearing surfaces of both parts of the anode and nipple are coated with electrode cement. The part to be attached is pushed

over the nipple sp that both anode parts are firmly in contact at the joint place d. The iron nipple b by means of the rod e is now screwed into the carbon nipple a from above, the abutment plate f is put in position and the nut g is screwed on. By screwing up the nut g the anode sections are pressed tightly together. If a rise in the bath voltage indicates that a loosening has taken place it is only necessary to screw up the nut g more 60 tightly. This device for pressing the parts together has the further great advantage that with its assistance anodes which are not round may be attached without it being necessary, as would otherwise be the case, to 65 adapt the one part of the anode to the other.

What I claim is:

1. Means for securing two sections of a carbon electrode together comprising a carbon nipple securely attached to the lower 70 part of the electrode and projecting into a recess in the lower end of the upper part, a second nipple mounted in the top of the first nipple and manually operated means for drawing said second nipple to cause the lower electrode section to be drawn tightly 75 into engagement with the upper electrode section.

2. Means for securing two sections of a carbon electrode together comprising a carbon nipple securely attached to the lower 80 part of the electrode and projecting into a recess in the lower end of the upper section of the electrode a second nipple provided in the top of the first nipple, said second nipple being screwed into an internally screw 85 threaded hole in the first nipple, a rod being connected to said second nipple and extending through a bore in said upper part of the electrode and a nut being provided on the top 90 of said rod for drawing said rod upwardly.

3. Means for securing two sections of a carbon electrode together comprising a carbon nipple securely attached to the lower 95 part of the electrode and projecting into a recess of the lower end of the upper section of the electrode a second nipple provided in the top of the first nipple, said second nipple being screwed into an internally screw 100 threaded hole in the first nipple, a rod being

connected to said second nipple and extending through a bore in said upper section of the electrode a plate on top of the upper section of the electrode the rod being supported 5 thereon.

4. Means for securing two sections of a carbon electrode together comprising a carbon nipple screwed into the lower part of the electrode and facing against shoulders in the 10 upper section of the electrode, a second iron nipple mounted in the top of the first nipple and manually operated means for drawing said second nipple to cause the lower electrode section to be drawn tightly into engagement with the upper electrode section. 15

In testimony whereof I affix my signature.

GEORG PEITZ.
